ELECTRICAL DISCHARGE DEVICE

Charles G. Smith, Medford, Mass., assignor to
 Raytheon Manufacturing Company, Newton,
 Mass., a corporation of Delaware

Application November 30, 1945, Serial No. 632,072

12 Claims. (Cl. 250—27.5)

1

This invention relates to an electrical discharge device and associated system of the type intended to convert direct current into alternating current of a desired frequency.

In order to avoid heavy and expensive apparatus, such as rotary converters usually required to convert direct current into alternating current, it has heretofore been proposed to utilize gaseous discharge devices having a plurality of main anodes, and to commutate the discharge from anode to anode in order to alter the direction of flow of the current through external circuits. Such constructions have not heretofore been commercially successful in the conversion of currents of high amperage and voltage due to the fact that the commutation has heretofore been secured by the action of an electromagnetic field upon the current stream in the discharge space of the tube. Such action of the magnetic field upon the discharge stream or current through the evacuated space of the tube is likely to diffuse the discharge so that it assumes the form of a distributed discharge. Under these conditions commutation of the discharge from one anode to an adjacent anode is not sharp and definite and may, therefore, result in unsatisfactory operation or in some cases in cessation of operation.

It is among the objects of the present invention to provide a construction of the type described in which the commutation of the discharge from one anode to another is effected by operating magnetically upon the arc spot of a mercury pool type cathode rather than upon the discharge stream between the cathode and anode.

A further difficulty, arising in connection with prior art devices of the type to which the invention relates, resides in the fact that at high voltages, due to the difference in potential between adjacent anodes, discharges might occur therebetween due to the high ionization existing in the discharge space at the instant of commutation of the discharge from one anode to another.

In the present invention such difficulty is obviated by the provision of a construction in which the distance between the successive anodes is much greater than the distance between the mercury pool cathode and any one of said anodes.

The foregoing and other objects and features of the invention will be made fully apparent to those skilled in the art from a consideration of the following detailed description taken in conjunction with the accompanying drawing in which:

Fig. 1 represents a top plan view of a tube con-

2

structed in accordance with the present invention together with a diagrammatic representation of a typical circuit with which it may be used; and

Fig. 2 is a cross-section taken along line 2—2 of Fig. 1.

Referring to the drawing, the tube comprises a glass envelope 6 in the form of an annulus or ring having a plurality of side tubes 7 projecting at spaced intervals from the upper surface thereof. The side tubes 7 provide at their upper ends seals for the anode lead-in conductors and supports 8 of the anodes 9 and 9'. A body of mercury 10 provides a mercury pool type cathode coacting with all of the anodes 9 and 9'. An auxiliary anode 11 above the mercury pool cathode 10 extends through the annular discharge space provided by the tubular envelope 6 and is supported by rods 12 in a position above the mercury pool cathode 10. The auxiliary anode 11 also extends between the surface of this pool and each of the anodes 9 and 9'.

A magnet 13 of U-shaped cross-section and having an annular energizing coil 14 is provided with a pair of annular pole pieces 15 and 16, one 25 of which lies within the annulus defined by the envelope 6 and the other 16 of which is positioned adjacent the outer circumference of the annular envelope 6.

The surface of the mercury pool 10 lies at or 30 only slightly below the upper surface of the annular pole pieces 15 and 16 so that the magnetic field between the pole pieces 15 and 16 is somewhat arched in the region of the surface of the mercury pool cathode 10.

Alternate anodes 9 are connected to one terminal 17 of the primary winding 18 of a transformer 19 having a secondary winding 20 and the intervening anodes which are designated 9' are connected to the other terminal 21 of said primary 40 winding 18. A condenser 22 is connected across the end terminals of the primary winding 18, and a center tap 23 on said primary winding is connected to the positive terminal 24 of a source of direct current which it is desired to convert into 45 alternating current of a definite frequency. The negative terminal 25 of said source of direct current is connected to the cathode pool 10. The auxiliary anode 11 is connected at one of the support rods 12 to a source of positive potential which 50 may be derived from the source of direct current across the main cathode-anode circuit at the terminals 24 and 25 through a current limiting resistor 26.

The operation of the construction described in 55 the foregoing is as follows:

Upon the application of a suitable potential between the auxiliary anode 11 and the mercury pool cathode 10, an arc spot formed at any point of the surface of the cathode pool 10 will be picked up by the auxiliary anode 11 to form a continuous arc between the auxiliary anode and the mercury pool cathode. In the instance shown a resistance-immersion ignitor 27 is provided to initiate the arc spot. It will be understood that various ignition means for initiating the arc spot upon the surface of the mercury pool cathode 10 are known in the art and that any such ignition device suitable for conventional mercury pool type tubes will be suitable for use in conjunction with the tube of the present invention. The discharge between the auxiliary anode 11 and cathode 10 having been initiated, the discharge between the auxiliary anode 11 and the cathode pool will be confined to a limited region of the tube extending in a more or less direct path between a relatively small cathode spot on the surface of the pool and some point on the anode 11 adjacent such spot. If there were no magnetic field extending across the surface of the pool the arc spot would travel about the surface of the pool in a haphazard manner and might move to the interior wall of the envelope 6 on either side of the mercury pool 10. Also, the arc spot would tend to move over the circular path provided by the annular form of the mercury pool within the tube, but such movement would be non-uniform since the arc spot might move irregularly in either direction. With a uniform magnetic field extending across the discharge space in a direction transverse to the lines of current flow between the auxiliary anode 11 and the cathode 10, the arc spot moves at a uniform speed in a direction normal to the lines of force of the magnetic field. The arc spot thus rotates about the generating axis of the annulus 6 and the slight arching of the magnetic field due to the position of the surface of the mercury pool adjacent the upper edges of the pole pieces 15 and 16 causes the arc spot to stay in or near the center of the pool. Also, when the field is acting in the region of the surface of the pool, rather than in the region between the anodes and the cathode pool, the field acts with reference to the arc spot on the surface of the pool and not with reference to the lines of current flow between the arc spot and the anodes. The effect of the field upon the arc spot is to drive the spot in a direction counter to the direction of ordinary motor action. In other words, considering the arc spot as the movable element, it is driven counter to the direction of rotation of a homopolar or unipolar motor. This motion of the arc spot in a direction counter to motor action will be called retrograde motion in contradistinction to the motion which would occur if the anodes were spaced at some distance from the cathode and the magnetic field applied across this space. Thus, with the field extending in the direction shown, the direction of movement of the arc spot would appear clockwise to the observer of Fig. 1.

The velocity of the arc spot in a tube where other conditions are constant will depend upon the strength of the magnetic field provided that the strength of the field is not above a critical value which will occur in the region of 5,000 gauss. Below this value the speed of the arc spot will vary substantially linearly attaining values of about 100 meters per second in the region of the upper critical value.

When the cathode-anode spacing is of the order of a few millimeters or greater, the pressure within the tube should not be greater than of the order of a centimeter of mercury, since above this upper limit of pressure the motion of the arc no longer is retrograde. If, however it is desired to utilize pressures above the order of a centimeter of mercury, then the electrode spacing must be decreased below the order of a few millimeters. I have found that with decreasing spacing the upper limit of pressure at which retrograde motion ceases increases.

As the arc spot moves into the region adjacent one of the main anodes 9 or 9', the discharge is transferred from one main anode 9 or 9' to another main anode. As the arc spot moves away from one of the main anodes the discharge between the main anode and the cathode 10 is discontinued. However, the arc spot continues to be maintained by a discharge between the auxiliary anode 11 and the cathode 10. When the arc spot moves past one of the main anodes 9, current from the positive terminal of the direct current source flows from the center tap 23 on the primary winding 18 to the end terminal 17 of said primary winding and thence to that one of the anodes 9 which the arc spot is approaching. Accordingly, an alternation will be induced in the secondary winding 20 of the transformer 19. After the arc spot has passed the anode 9 and moved to a position adjacent the next succeeding anode 9', a current will now flow from the center tap 23 to the other end terminal 21 of the primary winding 18. Thus, the current through the primary winding 18 is, on this occasion, in the opposite direction to the flow of current through the winding on the immediately preceding occasion, and an alternation will now be induced in the secondary winding 20 in the opposite direction to the current previously induced therein. Accordingly, alternating current may be taken from the end terminals of the secondary winding 20. Since the anodes 9 and 9' are symmetrically spaced around the circle defined by the envelope 6, and since for a uniform magnetic field the arc spot travels at a uniform angular velocity, the frequency of the alternating current output from the secondary winding 20 is influenced by the strength of the magnetic field; that is to say, for any given tube the output frequency will be determined by the distance between the successive anodes 9-9' and the strength of the magnetic field. Thus, for a tube of given geometry the output frequency may be varied within limits by varying the strength of the magnetic field. In the instance shown the strength of the field may be varied by means of a rheostat 28 in the supply line between a suitable source of direct current 29 and the coil 14. The output frequency may be stabilized by the provision of a resonant circuit including the primary winding 18. In the instance shown a stabilizing circuit is provided by the condenser 22 connected across the end terminals of the primary winding 18. The parameters of the resonant circuit are so chosen that the natural frequency of this circuit is correlated to the angular velocity of the arc spot, which, in turn, corresponds to the desired frequency of the alternating current output. Thus, small variations in the angular velocity of the arc spot, which would result in variations in the output frequency, are prevented by the resonant circuit which has the effect of holding the arc spot in the region of one of the anodes 9 or 9', when the arc spot is moving

at a velocity corresponding to a frequency higher than the desired frequency, or of pulling the arc spot into the region of one of the anodes if it has been retarded in its movement toward such region.

As previously stated, the output frequency can be varied by varying the magnetic field. Such variations in the magnetic field can be obtained by varying the current supplied to the coil 14. When so altered it is desirable that the frequency of the resonant circuit, including the condenser 22, be correspondingly altered so that it will again be equal to the desired output frequency. For this purpose a small variable inductance 30 may be interposed in the resonant circuit or the capacitance of the condenser 22 may be varied, or both.

In the form of the invention shown, the envelope 6 is of glass. However, it will be apparent to those skilled in the art that the envelope may be of other suitable materials. For example, as in the construction of conventional mercury vapor rectifiers, the envelope may be of metal, provided the anodes 9 are suitably insulated therefrom. However, the metal in this case should be non-magnetic, such as non-magnetic steel, or if of magnetic material the envelope should be so thin that it is readily saturated by the magnetic field imposed thereon so that upon saturation the material offers no further obstruction to the imposition of the magnetic field across the surface of the mercury pool.

While there has been herein described a preferred embodiment of the invention, other embodiments within the scope of the appended claims will be apparent to those skilled in the art from a consideration of the form shown and the teachings hereof. Accordingly, a broad interpretation of the claims, commensurate with the scope of the invention within the art, is desired.

What is claimed is:

1. A gaseous discharge device comprising an annular envelope containing a body of mercury providing an annular cathode, an annular anode spaced from said cathode, means for establishing an arc spot on said cathode, and means for imposing a magnetic field across the surface of said annular cathode effective to impart a retrograde motion to said arc spot.

2. A gaseous discharge device comprising an annular envelope containing a body of mercury providing an annular cathode, an annular anode coaxial with said cathode and disposed in a plane spaced from and parallel with the surface of said cathode, means for establishing an arc spot on said cathode, and means for imposing a magnetic field across the surface of said annular cathode effective to impart a retrograde motion to said arc spot.

3. A gaseous discharge device comprising an annular envelope enclosing a discharge space and containing a body of mercury providing an annular cathode pool, a plurality of main anodes evenly distributed in said discharge space of said tube, means for establishing an arc spot on said pool, the distance between two successive main anodes being greater than the distance of any of said anodes from said cathode, a magnet having a pair of annular pole pieces, one adjacent each side of said pool, the upper edges of the faces of said pole pieces lying in a plane closely adjacent the plane defined by the surface of said cathode pool, whereby said arc spot is driven in a direction counter to the direction of rotation of a homopolar motor and the discharge is commutated successively from one of said anodes to

another as said arc spot moves into proximity with first one anode and then another, and at least one auxiliary anode formulating said discharge when the arc spot is at points intermediate said main anodes.

4. A gaseous discharge tube for converting direct current into alternating current comprising an envelope providing an annular discharge space, an even number of main anodes positioned at regularly spaced intervals about said discharge space, a mercury-pool cathode coaxing with said anodes, at least one auxiliary electrode, means for establishing an arc discharge between said auxiliary electrode and said cathode, means for shifting said discharge through a predetermined orbital path whereby said discharge moves into proximity to said main anodes successively in the order in which said anodes are arranged about said discharge space, and whereby said discharge is commutated successively from one to another of said main anodes.

5. A gaseous discharge tube for converting direct current into alternating current comprising an envelope providing an annular discharge space, an even number of main anodes positioned at regularly spaced intervals about said discharge space, a mercury-pool cathode providing a continuous annular cathode surface coaxing with said anodes, an annular auxiliary electrode, means for establishing an arc discharge between said auxiliary electrode and said cathode, means for shifting said discharge through a predetermined orbital path whereby said discharge moves into proximity to said main anodes successively in the order in which said anodes are arranged about said discharge space, and whereby said discharge is commutated successively from one to another of said main anodes.

6. A gaseous discharge tube for converting direct current into alternating current comprising an envelope providing an annular discharge space, an even number of main anodes positioned at regularly spaced intervals about said discharge space, a mercury-pool cathode providing a continuous annular cathode surface coaxing with said anodes, at least one auxiliary electrode, means for establishing an arc discharge between said auxiliary electrode and said cathode, means for shifting said discharge at a predetermined velocity through a predetermined orbital path whereby said discharge moves into proximity to said main anodes successively in the order in which said anodes are arranged about said discharge space, and whereby said discharge is commutated successively from one to another of said main anodes.

7. A gaseous discharge tube for converting direct current into alternating current comprising an envelope providing an annular discharge space, an even number of main anodes positioned at regularly spaced intervals about said discharge space, a mercury-pool cathode providing a continuous annular cathode surface coaxing with said anodes, at least one auxiliary electrode, means for establishing an arc discharge between said auxiliary electrode and said cathode, magnetic means for shifting said discharge through a predetermined orbital path whereby said discharge moves into proximity to said main anodes successively in the order in which said anodes are arranged about said discharge space, and whereby said discharge is commutated successively from one to another of said main anodes.

8. A gaseous discharge tube for converting direct current into alternating current comprising

an envelope providing an annular discharge space, an even number of main anodes positioned at regularly spaced intervals about said discharge space, a mercury-pool cathode providing a continuous annular cathode surface coating with said anodes, at least one auxiliary electrode, means for establishing an arc discharge between said auxiliary electrode and said cathode, means for establishing a magnetic field transverse to said annular discharge space for shifting said discharge at a predetermined velocity through a predetermined orbital path whereby said discharge moves into proximity to said main anodes successively in the order in which said anodes are arranged about said discharge space, and whereby said discharge is commutated successively from one to another of said main anodes.

9. A gaseous discharge device comprising an envelope containing a body of mercury providing a cathode, an anode spaced from said cathode, means for establishing an arc spot on said cathode, and means for imposing a magnetic field across the surface of said cathode effective to impart a motion to said arc spot, the pressure within said envelope and the cathode-anode spacing being such that the motion of said arc spot is retrograde motion.

10. A gaseous discharge device comprising an envelope containing a body of mercury providing a pool cathode having an elongated surface providing a closed path, an anode spaced from said cathode, means for establishing an arc spot on said cathode, and means for imposing a magnetic field across the surface of said cathode effective to impart a motion to said arc spot around said closed path, the pressure within said envelope and the cathode-anode spacing being such that said arc spot is driven in a direction counter to the direction of rotation of a homopolar motor.

11. A gaseous discharge device comprising an envelope containing a body of mercury providing a cathode, an anode spaced from said cathode, means for establishing an arc spot on said cathode, and means for imposing a magnetic field across the surface of said cathode effective to impart a motion to said arc spot, the pressure within said envelope and the cathode-anode spacing being such that said arc spot is driven in a direction counter to the direction of rotation of a homopolar motor.

envelope containing a body of mercury providing a cathode, an anode spaced from said cathode a distance greater than a few millimeters, means for establishing an arc spot on said cathode, and means for imposing a magnetic field across the surface of said cathode effective to impart a motion to said arc spot, the pressure within said envelope being less than a centimeter of mercury, whereby the motion of said arc spot is retrograde motion.

12. A gaseous discharge device comprising an envelope containing a body of mercury providing a cathode, an anode spaced from said cathode a distance less than a few millimeters, means for establishing an arc spot on said cathode, and means for imposing a magnetic field across the surface of said cathode effective to impart a motion to said arc spot, the pressure within said envelope being greater than a centimeter of mercury, whereby said arc spot is driven in a direction counter to the direction of rotation of a homopolar motor.
